James L. Jackson. Design for Iron Railing

4378

PATENTED OCT 4 1870

Witness,

Chas H. Bush
Geo. A. Miller

James L. Jackson.

United States Patent Office.

JAMES L. JACKSON, OF NEW YORK, N. Y.

Design No. 4,378, dated October 4, 1870.

DESIGN FOR IRON RAILING FOR HORSE-STALLS.

The Schedule referred to in these Letters Patent and making part of the same

To all whom it may concern:

Be it known that I, JAMES L. JACKSON, of the city and State of New York, have invented and made a new and original Design for an Iron Railing, and the following is declared to be a correct description of the same.

The accompanying photographic view represents the said railing.

At the bottom ends of the vertical bars *a* are reversed, semicircular ornaments, *b*, connecting the bars *a* to each other, and also to the bottom rail *c*.

At the top of the bars *a* are ornamental ellipses, *d*, between said bars *a* and the top rail *e* of the railing.

In the middle portions of the bars *a* there are ornamental diamond-shaped connections, *f*.

This ornamental design of a railing is shown in connection with what is known as a ramp or iron railing, for the upper portion of the division between horse-stalls, but the same may be employed with a railing adapted to other uses.

I claim as my invention—

The design of the ornamental connections between the bars of an iron railing, as described and represented.

Signed this 8th day of August, A. D. 1870.

JAMES L. JACKSON.
